UNITED STATES PATENT OFFICE.

CARLTON H. LEE, OF BOSTON, MASSACHUSETTS.

DESIGN FOR A BOTTLE.

SPECIFICATION forming part of Design No. 23,399, dated June 26, 1894.

Application filed May 16, 1894. Serial No. 511,485. Term of patent 14 years.

To all whom it may concern:

Be it known that I, CARLTON H. LEE, of Boston, in the county of Suffolk and State of Massachusetts, have invented and produced a new and original Design for a Bottle, of which the following is a specification.

Reference is to be had to the accompanying drawings, forming a part of this specification, in which similar letters of reference indicate corresponding parts in all the figures.

Figure 1 is a front view of a bottle embodying my new design. Fig. 2 is a side view thereof; and Fig. 3 is an inverted plan view.

The leading feature of my design consists in the bottle, the body of which has in general the configuration of a human skull, the top

of the skull presenting rounding lines and the lines of the bottle neck rising from such rounded top. At the lower portion of the back and sides, the surface *a* appears depressed within the upper portion *b* of the back and side surfaces, and such depressed surface *a* rises to a higher point at the back than at the sides. At the bottom of the body appears the representation of cross bous. 25

I claim—

The design for a bottle herein shown and described.

CARLTON H. LEE.
